UNITED STATES PATENT OFFICE.

DOMINICK A. McDONALD, OF ROCKLAND, MAINE, ASSIGNOR TO McDONALD BOOT AND SHOE VENTILATING COMPANY, OF SAME PLACE.

BOOT AND SHOE.

SPECIFICATION forming part of Letters Patent No. 231,830, dated August 31, 1880.

Application filed June 12, 1880. (No model.)

To all whom it may concern:

Be it known that I, DOMINICK A. McDONALD, of Rockland, in the county of Knox and State of Maine, have invented a new and useful Improvement in Boots and Shoes; and I do hereby declare that the following is a full, clear, and exact description of the same.

My invention relates to the ventilation of boots and shoes, and is an improvement upon the device shown in Letters Patent granted me on the 13th day of April, 1880, numbered 226,532.

The invention consists of an air-chamber for more perfect ventilation, located centrally within the sole of the boot or shoe, about the ball of the foot, and provided with openings to the interior of the shoe, and with communication with the tubular passages of coiled wire, which extend upward and open to the outside. This air-chamber may be made in various ways.

In the drawings hereunto attached, Figure 1 represents a form of the chamber with communications in the bottom of an ordinary insole. Fig. 2 is a top view of the same insole. Fig. 3 is a section on line $x x$, and Fig. 4 a section on line $y y$ of Fig. 2.

In these figures, $a a$ represent the coil of wire, such as is shown in my patent heretofore referred to. This coil is represented as extending around within the sole of the boot or shoe and backward to the heel, whence each end extends upward along the side of the leg. Between the loop is located the air-chamber b . In the form shown it is made within the insole by cutting grooves in the under side both transversely and longitudinally of the sole, the transverse grooves opening into the groove in which the coil of wire is placed, and such transverse grooves are also provided with the tubular coils which keep them open and prevent the edges from being flattened by

pressure. These grooves form air-spaces, and as they are connected by numerous perforations $c c c$ with the interior of the boot or shoe, they form greatly-increased means of communication between the interior of the boot or shoe and the external air. Without such a chamber and the perforations connected therewith the only means of communication between the interior of the shoe or boot and the exterior would be through the holes $d d$, along the line of the coiled wire. This leaves the central part without ventilation—a part ordinarily most necessary to ventilate and most readily acted upon by the foot in walking.

The air-chamber described may be formed in other ways. The inner sole may be cut out and a piece of rubber, stamped or cut in the same shape as the leather sole above described, may be inserted in the place; or transverse grooves with lines of perforations may be used without the longitudinal grooves.

Manifestly the invention is equally applicable to rubber as to leather goods.

Having thus described my invention, what I claim is—

The described improvement, consisting of the chamber located in the sole and included within the loop of coiled wire, also in said sole, the said chamber being connected with the coil, and also having openings to the interior of the boot or shoe, the whole being arranged substantially as shown and described.

In testimony whereof I have signed my name to this specification in the presence of two subscribing witnesses.

DOMINICK A. McDONALD.
